UNITED STATES PATENT OFFICE

142,886

DESIGN FOR A MATCH DISPENSER

Francis R. McNine, Bridgeport, Conn.

Application January 9, 1945, Serial No. 117,360

Term of patent 7 years

(Cl. D48—28)

To all whom it may concern:

Be it known that I, Francis R. McNine, a citizen of the United States, residing at Bridgeport, county of Fairfield, State of Connecticut, have invented a new, original, and ornamental Design for Match Dispenser, of which the following is a specification, reference being had to the accompanying drawing, forming part thereof.

In the drawing:

Fig. 1 is a top plan view of a match dispenser, showing my new design;

Fig. 2 is a perspective view of thereof, and

Fig. 3 is a front elevation.

I claim:

The ornamental design for a match dispenser, substantially as shown.

FRANCIS R. McNINE.
